CLAIM

The ornamental design for an electrical connector as shown and described.

DESCRIPTION

FIG. 1 is a front perspective view of an electrical connector according to the present invention.

FIG. 2 is a rear perspective view of the electrical connector of FIG. 1.

FIG. 3 is a front view of the electrical connector of FIG. 1.

FIG. 4 is a rear view of the electrical connector of FIG. 1.

FIG. 5 is a left side view of the electrical connector of FIG. 1.

FIG. 6 is a right side view of the electrical connector of FIG. 1.

FIG. 7 is a top view of the electrical connector of FIG. 1; and,

FIG. 8 is a bottom view of the electrical connector of FIG. 1.

The dash-dot broken line portion of the drawing is included to show portions of the article that form no part of the claimed design. The dash-dot broken line portion of the drawings is included to show claim boundaries that form no part of the claimed design.

1 Claim, 8 Drawing Sheets
